UNITED STATES PATENT OFFICE.

JOHN ROWLAND BROWN AND KENNEDY PARK, OF MANSFIELD, OHIO.

WATER-TUBE BOILER.

No. 832,591.

Specification of Letters Patent.

Patented Oct. 9, 1906.

Application filed June 12, 1905. Serial No. 264,774.

To all whom it may concern:

Be it known that we, JOHN ROWLAND BROWN and KENNEDY PARK, of Mansfield, Richland county, Ohio, have invented a new and useful Water-Tube Boiler, of which the following is a full, clear, and exact description, reference being had to the accompanying drawings, forming part of this specification, in which—

10 Figure 1 is a vertical longitudinal section of our improved boiler on the line I I of Fig. 2. Fig. 2 is a cross-section on the line II II of Fig. 1; and Fig. 3 is a broken plan view, partly in section, showing the roof-baffle arrangement.

15 Our invention relates to that class of boilers wherein front and rear headers are connected by inclined water-tubes, and is designed to provide an improved arrangement 20 of the boiler wherein the water-tubes are provided with baffling arranged to fully extract the heat of the gases.

The further object of the invention is to provide a simple construction which may be 25 cheaply and easily made and not liable to get out of order.

In the drawings, 2 represents the front headers, and 3 the rear headers. These headers preferably extend vertically and are 30 provided with zigzag inner faces which are substantially at right angles to the axes of the water-tubes. The headers are preferably of sinuous form, as shown in Fig. 3, though the exact form and arrangement of 35 the headers may be varied without departing from our invention. The lower ends of the headers are connected by the large water-tubes 4, while above this horizontal row the smaller water-tubes are arranged, preferably, 40 in clusters of four each. Each cluster of four is expanded in suitable tube-seats in the headers, the headers being provided with hand-holes opposite each group.

45 Between the lower row of large tubes and the next rows of smaller tubes we provide a baffle 5, which preferably consists of fire-brick fitting on and between the larger tubes, as shown in Fig. 2. This baffle extends from the front of the furnace-chamber to an intermediate part of the tubes, its length being varied as desired, according to the character 50 of combustible used. From near the inner end of this baffle arises a vertical cross-baffle 6, which consists of fire-brick fitted between 55 the tubes and preferably extends the entire height of the tubes at this point in their

length. The gases are therefore compelled to pass upwardly across the rear portions of all of the water-tubes before they are allowed to pass forwardly. The upper ends of the rear headers 3 are provided with vertical faces and connected by the tubes 7 with the front transverse steam and water drum 8, which is connected to the front headers by nipples or tubes 9. Above the tubes 7 and 60 lying on them is a top baffle or roof 10, of fire-brick, which extends entirely across the rear portions of the tubes and forwardly to the line of the vertical baffle 6. In front of this plane of the vertical baffle the roof or baffle 70 10', which is an extension of the baffle 10, extends over the central rows of tubes between the vertical longitudinal baffles 11 11. These baffles 11 extend longitudinally of the tubes from intermediate points in the width 75 of the baffle 6. They project forwardly from the baffle 6 to the front headers and extend downwardly only a part of the depth of the water-tubes. The side portions of baffle 6 extend to the roof 10, while its portions between the baffles 11 stop above the tubes and leaves a central opening leading forward 80 below the roof. The vertical depth of these baffles may be varied as desired, and the gases which enter the front portion of the 85 boiler through the space or opening 12 in baffle 6 are compelled to flow downwardly under the baffle 10 and between the baffles 11 until they reach the lower ends of these baffles 11. The gases then divide and flow sidewise into 90 the spaces outside the baffles 11, whence they rise and pass upwardly to the transverse flue 13, which is connected to the stack.

We have shown the front headers as nipped into a rectangular mud-drum 14, extending transversely above the firing-doors and provided with blow-offs at its ends. We have also shown the combustion-chamber as arranged for the burning of oil. Thus the bars 15 support a fire-brick flooring 16, 100 which extends upwardly and rearwardly at an angle which is preferably substantially the same as the angle of the water-tubes. The burners project through the front doors and are preferably arranged horizontally, so that 105 their flames strike the fire-brick floor at a point intermediate of its length. If grate-bars are used for solid fuel, they will preferably be arranged in similar manner, being inclined rearwardly and upwardly corresponding to the angle of the tubes. To supply additional air to the combustion-chamber, we 110

preferably employ front air-doors 17 and rear air-doors 18, which are operated, respectively, by the ratchet device 19 and the ratchet-rods 20. By opening or closing these doors the air can be admitted to or shut off from the ash-pit. If the air is allowed to enter, it is heated by flowing through the rear doors underneath the fire-brick floor and then rises through suitable holes in the front portion of the floor. The rear portion of the mud-drum is preferably protected by a layer of fire-brick or refractory material 21.

In the operation of the boiler the flame and gases within the combustion-chamber flow underneath the baffle 5 and thence upwardly across the rear portions of all of the water-tubes. The gases then converge into the space between the upper water-tubes and the upper baffle 10 and flow forwardly between the baffles 11 and under the roof 10. They then flow downwardly among a portion of the water-tubes until they reach the lower ends of the longitudinal baffles 11 and then divide and flow upwardly through the opposite portions of the side tubes, whence they flow into the offtake and to the stack.

The advantages of our invention result from the peculiar arrangement of the baffle, which provides the passing of the gases over all of the water-tubes, while dividing the gases under the upward flow and causing them to flow laterally before they pass up over the water-tubes in their last upward pass. We have shown the boiler as having the firing-doors at the lower ends of the inclined tubes. Within the scope of our broader claims, however, the boiler may be fired at the other end—*i. e.*, beneath the higher ends of the tubes.

Having thus described the invention, what is claimed, and desired to be secured by Letters Patent, is—

1. A water-tube boiler having front and rear headers connected by inclined water-tubes, a substantially horizontal baffle extending from one end of the furnace-chamber for a part of the length of the tubes adjacent the bottom of the series of tubes, a vertical baffle extending across the tubes near the inner end of the horizontal baffle and rising therefrom, a roof extending over the end portions of the tubes beyond the horizontal baffle, and succeeding baffles arranged to pass the gases downwardly and thence downwardly and upwardly over the end portions of the tubes, the gases being divided in one of the last passes; substantially as described.

2. A water-tube boiler having front and rear headers connected by inclined water-tubes, a substantially horizontal baffle extending over a portion of the furnace adjacent the bottom of the series of tubes, a vertical cross-baffle extending upwardly from the inner portion of the horizontal baffle, a roof extending over the tubes and having an

outlet or outlets to the stack-flue, longitudinal baffles extending from the cross vertical baffle for a part of the depth of the water-tubes, and an upper horizontal baffle or baffles extending from the vertical cross-baffle to the ends of the tubes and compelling the gases to divide and flow sidewise among the water-tubes before they rise to the stack; substantially as described.

3. A water-tube boiler having front and rear headers connected by inclined rows of water-tubes, a horizontal baffle extending over at least one row of water-tubes and from the ends of the tubes to a point intermediate their length, a vertical cross-baffle extending from the end of the horizontal baffle across the entire rows of inclined tubes, tubes extending from the headers at one end to a transverse steam and water drum at the other end, a roof or baffle over the last-named tubes and having an exit or exits to the stack, vertical longitudinal baffles extending from intermediate points in the vertical cross-baffle to one end of the tubes, and an upper baffle or baffles beneath the offtake and arranged to cause the gases to divide and flow laterally as they pass over the end portions of the tubes to the stack; substantially as described.

4. A water-tube boiler having front and rear headers connected by rearwardly and upwardly inclined tubes, the firing-doors being at the lower end, a baffle extending from the front end of the furnace rearwardly over the furnace-chamber, a vertical cross-baffle extending upwardly from the inner end of the lower baffle, a roof over the tubes having outlets to the stack, and longitudinal vertical baffles extending forwardly from the vertical cross-baffles and depending a part of the depth of the tubes, the gases dividing and flowing laterally in front of the vertical cross-baffle and over the end portions of the water-tubes as they rise to the stack; substantially as described.

5. A water-tube boiler having front and rear headers connected by inclined water-tubes, a lower horizontally-extending baffle, intermediate cross-baffle having an opening or openings in its upper portion, a roof across the top of the tube-chamber having an opening or openings to the stack, and longitudinally-extending vertical baffles arranged to cause the gases to divide and flow laterally before they rise to the stack; substantially as described.

6. A water-tube boiler having front and rear headers connected by inclined water-tubes, a baffle extending over the lower tubes for a part of their length, a vertically-extending cross-baffle having a closed top portion with a central opening, longitudinally-extending vertical baffles extending from the sides of the cross-baffle opening to the ends of the tubes, and an upper roof having side

openings to allow the divided currents of gases to flow upwardly to the stack; substantially as described.

7. A water-tube boiler having front and rear headers, water-tubes connecting the headers, a substantially horizontal baffle terminating short of one end of the boiler and defining the top of the fire-box, a cross-baffle rising from the inner end of the substantially horizontal baffle and extending to the roof of the boiler, there being a flue-passage through the top portion of the upright baffle,

and upright baffles leading from opposite sides of the flue-passage above the substantially horizontal baffle and defining upright flue-passages, the roof having flue-openings for the upright flue-passages. 15

In testimony whereof we have hereunto set our hands.

J. ROWLAND BROWN.
KENNEDY PARK.
